(57) **CLAIM**

I claim the ornamental design for a specimen container support rack, as shown and described.

DESCRIPTION

FIG. 1 is a top perspective view of a specimen container support rack, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof;

FIG. 9 is a front elevation view thereof showing a configuration of use; and,

FIG. 10 is a top perspective view thereof showing a configuration of use.

The broken lines in the drawings depict environment that does not form a part of the claimed design.
